AURIN M. CHASE, OF SYRACUSE, NEW YORK.

INTERNAL-COMBUSTION ENGINE.

1,037,437.

Specification of Letters Patent. Patented Sept. 3, 1912.

Application filed September 29, 1910. Serial No. 584,398.

To all whom it may concern:

Be it known that I, AURIN M. CHASE, of Syracuse, in the county of Onondaga and State of New York, have invented a certain 5 new and useful Internal-Combustion Engine, of which the following is a specification.

This invention relates to two cycle internal combustion engines, and has for its 10 object means for detaining some of the incoming charge in the combustion chamber near the point of ignition; and it consists in the combinations and constructions hereinafter set forth and claimed.

15 In describing this invention reference is had to the accompanying drawings in which like characters designate corresponding parts in all the views.

Figure 1 is a vertical sectional view of 20 the cylinder of my engine, the piston being also shown in the cylinder. Fig. 2 is a sectional view on line "A—A", Fig. 1.

1 is the cylinder; and 2 is the piston movable in the cylinder. The cylinder is provided with the usual inlet and outlet ports 25 3 and 4 opening into the cylinder in front of the position occupied by the piston head when the piston is at the limit of its out stroke, as seen in Fig. 1. The cylinder is 30 also provided preferably with a dome-shaped head 5 forming the combustion or compression chamber 6 and such head 5 is formed with an opening at the highest point in which a spark plug is arranged.

35 The cylinder is also provided with means for obstructing the incoming charge and forming a pocket for detaining in the combustion chamber some of such charge while pure and unmixed with the burned gases of 40 the previous firing, such means comprising a diaphragm 8 projecting from one of the cylindrical walls of the cylinder near the head thereof, and extending but part way across the chamber of the cylinder. As here

45 shown such obstruction projects from the cylindrical wall of the cylinder located diametrically opposite to that wall through which the inlet port 3 opens and is located just in front of the position occupied by the 50 piston head when the piston is at the limit of its stroke as indicated by dotted lines, Fig.

1. This obstruction or diaphragm 8 is of sufficient size only to cause the pure gas to bank around the electrodes of the spark plug, 55 and as here shown said diaphragm 8 extends less than half way across the cylinder so

that the greater part of the chamber of the cylinder is open to most of the outward and downward force of the explosion radiating from the electrodes of the spark plug, these 60 electrodes being located above the diaphragm and near a line extending parallel to the direction of movement of the piston and between the edge of the diaphragm and the opposite wall of the cylinder, so that the 65 more direct downward radiations of the explosion go directly to the piston and are not obstructed or deflected by the diaphragm 8. As here shown the spark plug is arranged coaxially with the cylinder.

70 The piston 2 is provided with the usual deflectors 9 and 10 for, respectively, directing the incoming charge from the inlet port 3 upwardly along one side of the cylinder into the combustion chamber and for deflecting the burnt gases through the exhaust ports 4. The exhaust ports 4 may be connected in the ordinary manner to the usual exhaust pipe and the inlet port 3 may be connected to a suitable supply for the motive fluid and as shown such port 3 communicates through a conduit 11 with the portion of the cylinder in rear of the piston through the opening 12 in the trunk of the piston and such portion of the cylinder in 85 rear of the piston communicates directly with the crank case, not shown.

75 In operation the incoming charge passes upwardly along one side of the cylinder and is deflected downwardly toward the piston head and expels the burnt charge of the previous firing and some of such incoming charge is obstructed by the diaphragm 8 and detained about the terminals of the spark plug 7. The portion of the charge which 80 is pure, that is, unmixed with burned gases of the previous firing, is detained by the diaphragm so that ignition of the gas is insured and the engine can be more easily controlled, owing to the fact that the throttling thereof can be made more nearly perfect than in two cycle engines heretofore in use.

85 It will be particularly noted that the obstruction for detaining the charge is located 90 entirely within the cylindrical wall of the cylinder.

95 What I claim is:—

100 1. In a two cycle internal combustion engine, a cylinder, and a piston movable in the cylinder, the cylinder having inlet and 105 exhaust ports located in front of the posi-

tion occupied by the piston head when the piston is at the limit of its out stroke, and the cylinder also having a diaphragm in its compression chamber extending part way across such chamber, the diaphragm projecting from the opposite side of the cylinder from that on which the inlet port is located, and a spark plug having its electrodes exposed within the main part of the chamber of the cylinder above the diaphragm near a line extending parallel to the direction of movement of the piston and between the edge of the diaphragm and the opposite wall of the cylinder, substantially as and for the purpose described.

2. In a two cycle internal combustion engine, a cylinder, and a piston movable in the cylinder, the cylinder having inlet and exhaust ports located in front of the position occupied by the piston head when the piston is at the limit of its out stroke, and

the cylinder also having a diaphragm in its compression chamber extending part way across such chamber forming a pocket for the gas, the pocket being arranged on the opposite side of the cylinder to that on which the inlet port is located, the wall of the compression chamber being curved to deflect the incoming charge into said pocket, and a spark plug supported by the cylinder and having its electrodes located near such pocket above the diaphragm, substantially as and for the purpose described.

In testimony whereof, I have hereunto signed my name in the presence of two attesting witnesses, at Syracuse, in the county of Onondaga, in the State of New York, this 23rd day of Sept., 1910.

AURIN M. CHASE.
